HARRY A. COCHRAN, OF HOUSTON, TEXAS, ASSIGNOR TO AMERICAN AUTOMATIC
WATER HEATER CO., A CORPORATION OF ARIZONA.

GAS-BURNER.

1,183,955.

Specification of Letters Patent.

Patented May 23, 1916.

Application filed July 2, 1914. Serial No. 848,547.

To all whom it may concern:

Be it known that I, HARRY A. COCHRAN, a citizen of the United States, residing at Houston, in the county of Harris and State 5 of Texas, have invented certain new and useful Improvements in Gas-Burners, of which the following is a specification.

This invention relates to new and useful improvements in gas burners.

10 The object of this invention is to provide a burner of the character described which is specially adapted to be used in connection with water heaters, and other heating apparatus, and is so constructed as to prevent 15 "back firing" and is also so formed that it may be placed to one side of the heating coil, rather than underneath it, so that the liquid which condenses on the coil will not fall on the burner.

20 The flame from gas burners now in most common use extends directly upwardly from the burner so that said burner must be placed directly underneath the coil to be heated and the water and moisture which 25 condenses on the coil falls upon the burner and injures the same. The flame from the burner herein described issues through the discharge opening in a forward direction so that said burner can be placed at one side of 30 the coil and be effective in heating the same and at the same time be protected from the moisture falling from the coil.

Another object of this invention resides in the provision of a construction which will 35 prevent the flashing or back-firing of the burner, as will be hereinafter set forth.

With the above and other objects in view, the invention has particular relation to certain novel features of construction, operation 40 and arrangement of parts, an example of which is given in this specification and illustrated in the accompanying drawings, wherein—

Figure 1 is a front elevation of the 45 burner, illustrating an embodiment of my invention. Fig. 2 is a vertical section through the same on the line *a—a* of Fig. 1. Fig. 3 is a plan view of the upper portion of the burner with the cap plate removed, and 50 Fig. 4 is a horizontal section on the line *b—b* of Fig. 1.

Referring now more particularly to the drawings, wherein like numerals of reference designate similar parts in each of the 55 figures, the numeral 1 refers to the tubular

body or shell, as used in connection with a gas and air mixer of the ordinary type. The shell surrounds a supply passage 2 for gas and air and is flared slightly at its lower end, which is open for the admission of air 60 and into which a gas supply pipe 3 projects. The upper portion of the body 1 is enlarged, as at 4, forming a discharge chamber, which, as shown in Fig. 3, is rectangular in cross section and is entirely open above. 65

A perforated diaphragm 5, which is preferably formed of wire gauze, is fitted over the open end of the discharge chamber and is held in a substantially transverse position thereto by a cap plate 6, of similar contour 70 to the discharge chamber, between which plate and discharge chamber the diaphragm is clamped by the screws 7. It should be stated that the diaphragm declines slightly forwardly. The underside of the cap plate is 75 concaved, or hollowed out, so as to maintain a space 8 between the cap plate and the diaphragm, as shown in Fig. 2 and a slot 9 extends across the cap plate, forming an oblong discharge opening and said cap plate 80 has an over hanging flange 10 in the rear of said discharge opening which deflects the blaze issuing from the discharge opening forwardly, and this flange is extended forwardly and over hangs said discharge opening so as to protect the diaphragm. 85

In operation, combustion of the mixture of gas and air which enters the chamber 4, through the supply passage 2, is maintained at or near the openings in the portion of the 90 diaphragm 5 opposite the discharge opening 9 and an unbroken flame is thrown out upwardly through said discharge opening and deflected laterally and forwardly by the flange 10 against the heating coil and the 95 burner will thus be efficient in heating the coil without being placed thereunder, so that the water which is condensed on or may leak from the heating coil will not fall on the burner and find its way through the joint 100 between the discharge chamber and cap plate and injure the interposed diaphragm.

The construction of the burner as hereinbefore described will also prevent any "back firing," that is, the mixture in the supply 105 passage 2 cannot become ignited from the flame issuing from the discharge opening 9, inasmuch as the cap plate 6 declines at such a small angle and the flame, while it is deflected forwardly, it is also deflected up- 110

wardly and there is no liability of its passing downwardly and into the air passageways at the lower end of the shell 1.

What I claim is:—

- 5 1. The combination with a gas and air mixing chamber, of an expanded discharge chamber, a direct passageway connecting said mixing chamber with said discharge chamber, a foraminous diaphragm arranged angularly relative to the discharge chamber and extending across the end of said chamber, a cap plate secured to the discharge chamber above the diaphragm and having an oblong slot forming a discharge opening therethrough, and a deflector arranged above and extending angularly over said opening.
- 10 2. The combination with a gas and air mixing chamber, of an enlarged discharge

chamber communicating with said mixing chamber and having an open end, a foraminous diaphragm extending across the end of the discharge chamber and arranged obliquely relative thereto, a cap plate secured to the discharge chamber above the diaphragm and having an oblong slot forming a discharge opening therethrough and a deflector carried by the cap plate and overhanging the discharge opening, and deflecting the blaze issuing through the opening.

In testimony whereof I have signed my name to this specification in the presence of two subscribing witnesses.

HARRY A. COCHRAN.
